ASH TRAY OR SIMILAR ARTICLE

Edward San Giovanni, Ridgefield, Conn.

Application February 1, 1949, Serial No. 610

Term of patent 3½ years

(Cl. D85—2)

To all whom it may concern:

Be it known that I, Edward San Giovanni, a citizen of the United States of America, residing at Ridgefield, in the county of Fairfield and State of Connecticut, have invented a new, original, and ornamental Design for an Ash Tray or Similar Article, of which the following is a specification, reference being had to the accompanying drawing, constituting a part hereof:

Fig. 1 is a perspective view of an ash tray or similar article, showing my new design;

Fig. 2 is a plan view thereof; and

Fig. 3 is a frontal edge view of the same.

I claim:

The ornamental design for an ash tray or similar article, substantially as shown.

EDWARD SAN GIOVANNI.
